(57) **CLAIM**

The ornamental design for a two wheel scooter as shown and described.

DESCRIPTION

FIG. 1 is a perspective illustration of a two wheel scooter as seen from the front and off-center from the front-to-back axis of the two wheel scooter;

FIG. 2 is a front elevation view of a two wheel scooter;

FIG. 3 is a rear elevation view of a two wheel scooter;

FIG. 4 is a first side elevation view of a two wheel scooter;

FIG. 5 is a side elevation view of a two wheel scooter from the side opposition to the side in FIG. 4;

FIG. 6 is top plan view of a two wheel scooter; and,

FIG. 7 is a bottom plan view of a two wheel scooter.

The broken lines are for the purpose of illustrating portions of the two wheel scooter that form no part of the claimed design.
